ATTORNEY

UNITED STATES PATENT OFFICE.

ROSE C. HANSGEN, OF PHILADELPHIA, PENNSYLVANIA.

LATCH-KEY CARRIER.

1,313,851.

Specification of Letters Patent.

Patented Aug. 19, 1919.

Application filed August 10, 1915. Serial No. 44,782.

To all whom it may concern:

Be it known that I, ROSE C. HANSGEN, a citizen of the United States, and a resident of the city of Philadelphia, county of Philadelphia, and State of Pennsylvania, have invented certain new and useful Improvements in Latch-Key Carriers, of which the following is a specification.

This invention relates to the devices by means of which a latch key may be securely carried without inconvenience beneath the skirt, and may be permanently attached to some indispensable portion of the wardrobe, such for instance, as from the corsets or from a hose supporter. The invention has for one of its objects the suspending of a latch key from the hose supporter in such a manner that the key may be readily removed or detached therefrom without substantially lifting the skirt; the providing of a clasp or snap hook which fits the sides of the key when supported therein, to prevent the key from turning with respect to the snap hook or becoming accidentally loosened or freed therefrom.

A further object of my invention is to suspend a latch key, and the device for holding the same, freely from the clasp of a hose supporter, by a strong flexible connection, such for instance, as a braided cord, flat tape, or strong flat ribbon, and in such a manner that the said connection is not liable to become twisted or knotted while being worn.

Further objects of my invention will appear in the specification and claims below.

Referring now to the drawing forming a part of the specification, and in which the same reference characters are used to designate the same parts throughout the various views:

Figure 1 is a view of my invention, showing the manner in which the device and the key supported thereby are attached to and suspended from a hose supporter, and showing the relative length of the flexible connection by means of which the snap hook is attached to the supporter and whereby the key may be readily detached from the snap hook without substantially lifting the skirt;

Fig. 2 is a front elevational view of the latch key carrier, with the latch key attached thereto, and permanently attached to the hose supporter by looping the flexible connection through the metal loop or eye of the hose supporter;

Fig. 3 is a side elevational view of the same;

Fig. 4 is a cross-sectional view of the metal clamp by means of which the ends of the flexible connection are attached to the ring of the swiveled portion of the snap hook;

Fig. 5 is a longitudinal view of the metal clamp shown in Fig. 4, and Fig. 6 is a view of a modification of the invention indicative of the way in which the snap hook may be attached to the metal loop or eye of the hose supporter by means of a flexible knotted woven cord.

To the metal loop or eye 1 of the hose supporter 2, through which passes the button 3 for securing the fastening the hose to the supporter, is tied, looped or otherwise permanently secured a flexible connection 4, the lower ends of which pass through the ring 5 of the swiveled portion 6 of the snap hook 7, and folded back on themselves are securely and permanently held connected together by means of a metal clamp 8. This metal clamp 8, more particularly illustrated in Fig. 4, consists of a small plate of metal having its side edges bent and turned over on to the body thereof, and its top and bottom edges provided with teeth or serrations 9, which, when the sides are folded over and around the cord, tape or ribbon are pressed together to increase the holding and gripping action of the clamp and prevent the free ends of the flexible connection from being pulled out of said clamp.

The swiveled portion 6 of said snap hook is permanently attached to the head 10 thereof so that the hook portion thereof may turn as a whole with respect to said swiveled portion 6. The head 10 of the snap hook 7 preferably passes through a hole or opening in the swiveled portion 6 and is preferably upset or headed over so as to prevent the removal or detachment of the hook with respect to said swivel.

The snap hook 7 consists of a closed metal loop structure, the upper sides 11-11' of which diverge considerably from each other until they reach points a little below the middle of the loop, and the lower sides 12-12' of which then more abruptly approach each other until the lower ends of said portions are relatively near each other, from which point they extend downwardly forming parallel side portions 13-13', the lower ends of which unite to complete said

- closed loop. The distance between the inner sides of the parallel portions 13—13 at the lower end of the snap hook is slightly greater than the thickness of a latch key 14, so that when a latch key is inserted into the loop and is supported from the bottom thereof, the opposite sides of said key will lie rather closely adjacent the parallel sides 13—13 of the snap hook.
- 10 The upper side 11' of the snap hook is preferably secured to the head 10 by a pivot or pin 15, and within the head 10 is a spring 16 tending to hold the beveled free end 17 of the side 11' against a correspondingly beveled end 18 of the hook. The side 11' thus forms a spring latch tending to hold the snap hook closed but permitting a key to be inserted into or removed from the snap hook when the latch 11' is depressed.
- 20 In the preferred form of my invention, the flexible connection 4 is a soft tubular braided cord and may be in the form of a relatively long flexible loop, so that when the upper end of the said loop is inserted through the 25 metal eye 1 of the hose supporter, the snap hook 7 may be then inserted through the loop of the flexible connection, and the flexible connection may then be tightly drawn, thus tying or knotting the said connection 30 to the lower end of the metal eye 1. This flexible connection 4 should be of a length to permit the snap hook 7 and key 14, carried thereby, to be suspended at a point a little below the knee, and when so arranged and 35 attached the key may be readily removed from the snap hook 7 without substantially lifting the skirt. To remove the key from the snap hook 7 it is only necessary for the wearer to stoop, bending the knees, and allowing 40 the key to move downwardly to a position substantially on a level with the floor or the lower hem or edge of the skirt, and to then depress the latch 11' with the thumb or finger and slide the key out of the snap 45 hook. The parallel sides 13—13 of the lower part of the snap hook hold the key relatively closely so that the said key may not be accidentally slipped off the hook and so that if there is a tendency for the key to 50 rotate on its longitudinal axis while being worn, due to the motion of the body, as for instance, in walking, it will not rise in the hook, but will turn the snap hook on its swivel with the key. A round braided cord, 55 in addition to being strong and flexible, does not wear as rapidly as a tape or ribbon, and is therefore preferable for the purpose.
- The side or latch 11' is made relatively long so that it extends to substantially the 60 widest portion of the loop of the snap hook, thus providing a latch long enough to be depressed by the fingers and permitting sufficient space for the passage of the key between the free end of the hook (when the 65 latch is depressed) and the finger, and the

wide portion of the loop is to provide space for the relatively long distance between the opening or hole 14' of the key and the top of the key.

In Fig. 6 is illustrated a manner of attaching the snap hook swivel to the eye of a hose supporter of a single length of cord 4', preferably woven of tubular form, the ends of said cord being provided with knots 19—19 and then tied respectively to the hose 75 supporter eye 1 and the swivel 5 by knots 20—20.

By reason of the flexible connection 4 and the swivel 5 and the prevention of the turning of the key 14 on its axis with respect to 80 the snap hook 7, the connection 4 does not become twisted or knotted when the same is worn by reason of any motion of rotation which the key may receive while the wearer is walking because the latch and the key are 85 free to turn together with respect to the flexible connection and said flexible connection freely adapts itself to any position of the body. Being freely suspended from the hose supporter it in no wise inconveniences 90 the wearer because the key and snap hook normally hang below the knee in such a manner that the wearer is not liable to sit upon the key or upon the snap hook and thus accidentally depress the latch and free the key 95 from the snap hook. Moreover, neither the key nor the snap hook will show through the skirt or clothing on account of the free manner in which it is suspended and this free suspension of the hook and key prevents 100 the same from wearing either the hose or the clothing in contact therewith.

With this device a latch key may be always carried by the wearer without any inconvenience whatever and inasmuch as it is 105 adapted to be permanently secured to an indispensable part of the apparel, it will be substantially always carried and will be, therefore, always available when needed.

What I claim and desire to protect by 110 Letters Patent is:

1. A latch key carrier comprising the combination of a snap hook having a relatively wide upper portion and a relatively long narrow lower end, the inner sides of said lower 115 end being substantially parallel and separated by substantially the thickness of an ordinary latch key, a spring pressed latch normally holding said hook closed and forming a side of said wide portion, a swivel at 120 the top of said snap hook, and a flexible fabric connection attached to said swivel and of a material adapted to be securely tied to a hose supporter, whereby said hook is freely rotatable on said swivel on an axis 125 substantially coincident with the end of said flexible connection and the rotation of said hook does not twist said flexible connection.

2. A latch key carrier comprising the combination of snap hook including a swivel at 130

the top thereof, of a flexible connection of soft material permanently attached to said snap hook, said connection being of a length to hold said hook suspended at a position 5 a little below the knee of the wearer when the upper end of said flexible connection is attached to a hose supporter, whereby the rotation of said hook does not twist said flexible connection and said hook may be 10 brought to a position at or about the lower edge of the skirt of the wearer by bending the knees.

3. A latch key carrier comprising the combination of a snap hook having a relatively 15 wide upper portion and a relatively long narrow lower end, the inner sides of said

lower end being substantially parallel and separated by substantially the thickness of an ordinary latch key, a spring pressed latch normally holding said hook closed and forming a side of the said wide portion, a swivel at the top of said snap hook, a flexible fabric connection, said swivel being attached to said fabric connection whereby said hook is freely rotatable on said swivel 20 on an axis substantially coincident with that of the end of said flexible connection and the rotation of said hook does not twist said flexible connection.

In witness whereof I have hereunto set 30 my hand this 10th day of August 1915.
ROSE C. HANGEN.
